UNITED STATES PATENT OFFICE.

ALBERT M. BUTZ, OF OAKPARK, ILLINOIS.

THERMOSTATIC HEAT-REGULATOR.

SPECIFICATION forming part of Letters Patent No. 739,055, dated September 15, 1903.

Application filed February 17, 1900. Renewed February 12, 1903. Serial No. 143,144. (No model.)

To all whom it may concern:

Be it known that I, ALBERT M. BUTZ, a citizen of the United States, residing at Oakpark, in the county of Cook and State of Illinois, have invented certain new and useful Improvements in Thermostatic Heat-Regulators, of which the following, when taken in connection with the drawings accompanying and forming a part hereof, is a full and complete description, sufficient to enable those skilled in the art to which it pertains to understand, make, and use the same.

This invention relates to a thermostatic heat-regulator to be attached to an ordinary diaphragm-controlled steam-valve on a steam heating-radiator; and its object is to obtain a thermostatic heat-regulator simple in construction, effective in operation, and not liable to get out of order.

A further object of this invention is to obtain a mechanism whereby in the thermostatic operation thereof communication between the diaphragm-chamber of an ordinary diaphragm-controlled steam-supply valve and the atmosphere will be closed prior to the establishment of communication between the source of supply of air under pressure and such diaphragm-chamber and also in such thermostatic operation of the mechanism communication between the source of supply of air under pressure and such diaphragm-chamber will be closed before establishing communication between such diaphragm and the atmosphere.

In the drawings referred to as forming a part hereof, and in which a reference-letter applied to indicate a given part is used to designate such part throughout the several figures, Figure 1 is an elevation of a thermostatic heat-regulator embodying this invention with the necessary adjuncts for its operation; Fig. 2, a vertical sectional view of an air-valve forming an element in the thermostatic heat-regulator illustrated in Fig. 1, on an enlarged scale, such valve being closed; and Fig. 3, a vertical sectional view of a portion of the valve illustrated in Fig. 2, on a still larger scale, with the valve open. Fig. 4 is a vertical sectional view of the apparatus illustrated in Fig. 1, and Fig. 5 is a dia-

grammatic view showing both air-valves with their connections in section. The several parts illustrated in Figs. 1 and 2 are in proper relative position for the valve illustrated in Fig. 2 to be closed and the valve illustrated in Fig. 5 to be opened.

A is the base of the thermostatic heat-regulator embodying this invention. B is the expandible member of such thermostatic heat-regulator. Expansible member B preferably consists of a tube, of ordinary expandible hard-rubber material, firmly held in support C, which support for appearance sake may be placed midway, or nearly so, of the tube and the inner rod b', extending through the tube B and secured at one end to such tube, as by connection D, and at the other end pivotally secured to the lever E, as by pivot e. Lever E consists of a U-shaped arm fulcrumed, as at e', to head B' of expandible member B. Head B' is secured to the tube B, so that the expansion of that portion of such tube between the support C and such head B' moves the head B' and the pivot e' in ear e' relative to the fulcrum e, thereby moving the lever E on such fulcrum e. The portion of the tube B between the support C and the head D, secured therein at one end of such tube, moves the head D and rod b', secured in such head, longitudinally, together with the fulcrum e, relative to pivot e', thereby moving the lever E. The relative position of the fulcrum e and pivot e' is therefore the same when the tube is held nearly midway thereof in support C as if such support C were at one end of such tube. The inner rod b' is of such material as to not expand under a slight variation of temperature to as great an extent as does the tube B. The location of the support C on the tube B is immaterial.

F is an air-pressure-supply tank—that is, a tank containing air at a pressure sufficient to force the diaphragm in diaphragm steam-valve G into an advanced position, thereby closing such valve to the admission of steam from steam-pipe A into radiator I when air from such supply-tank is admitted to the diaphragm-chamber.

i is a nipple connecting the diaphragm-valve G with the radiator I.

J is an air-conduit extending from the supply-tank F to valve K, discharging air from such supply-tank to such valve.

L is a conduit extending from valve K to valve K'.

K' is an air-valve, the duplicate of air-valve K, except that the diaphragm k' (see Fig. 2) is punctured or omitted therefrom, and in valve K the inlet-conduit J discharges into one chamber of the valve, and the conduit L (connecting the valves) extends from the other chamber, while the discharge-conduit M of valve K' extends from the same chamber of such valve that the connecting-conduit L discharges into. Conduit M extends from valve K' to the diaphragm-chamber of valve G. Valves K K' are respectively secured to support C, as by band K² and screws K³ K³.

When valve K is open, air is discharged from such valve through the passage-way or conduit L into valve K', and valves K K' being arranged relative to lever E so that but one thereof can be opened at a given time such air will pass from valve K' to and through passage-way or conduit M to the diaphragm chamber or valve G and close such valve by expanding the diaphragm thereof.

Diaphragm-valve G is an ordinary diaphragm-valve, forming no part of this invention, and is not, therefore, described in detail.

The construction of the valves K K' is well illustrated in Figs. 2, 3, and 5 and comprises, respectively, the tube k , forming the casing of the valve, such tube being open at one end in valve K' and closed in valve K at such end by the diaphragm k' (preferably of rubber) and at the other end by the end k^2 . The casing k is divided into two chambers by the plug k^3 and band k^4 , such band being preferably of rubber. In valve K conduit J discharges into one of the chambers of the valve-casing, and the conduit L is in communication with the other chamber.

k^5 is a valve-stem passing loosely through the centrally-extending hole k^6 in plug k^3 , near to the diaphragm k' in valve K and to about the same location in the valve-casing thereof as in valve K', such diaphragm k' being removed, however, (see Fig. 5,) and k^7 is a valve on the end of such valve-stem k^6 . The end of passage-way k^6 which is adjacent to the valve k^7 is provided with a valve-seat thereto, and the valve k^7 is provided with rubber disk k^8 , fitting on such valve-seat.

k^9 is a spring surrounding the valve-stem and yieldingly holding the valve k^7 on its seat k^8 by pressing against said valve at one end and against an arched end plate k^{10} in the end of the valve-casing. This end plate k^{10} receives through a perforation the headed end of valve-stem k^5 and is sufficiently arched to permit of a movement of said headed end between the plate k^{10} and the end of the valve-casing.

In valve K' the casing is divided into two chambers, into one of which chambers the conduit L discharges and from which the con-

duit M extends. When the valve K is opened, air under pressure passes from conduit J through the valve into and through the conduit L, into one of the chambers of valve K', and such valve being closed such air under pressure will pass from such chamber into the conduit M and into the diaphragm-chamber G, closing such valve. The opening of valve K is obtained by arm e^3 of lever E being forced by the expansion member B into such position that the projection e^4 (see Fig. 2) on the end of arm e^3 compresses the diaphragm k' , forcing the valve-stem k^5 backward, so unseating the valve-plug k^7 .

k^4 k^4 are caps of valves K K', respectively, these caps having apertures K^5 therein, respectively, through which a projection on lever E passes to move the valve-rod k^5 against the resiliency of spring k^9 . Arm e^5 , Fig. 1, or arm e^9 , Fig. 4, of lever E forces back the valve-stem of valve K' in like manner as arm e^3 of such lever E forces back the valve-stem of valve K, as last above described, when the expandible member B of the thermostatic valve is oppositely operated, thereby opening the valve K'—that is, thereby forcing the valve thereof off its seat—so that the two chambers in such valve are in communication with each other in the manner described relative to valve K, and the diaphragm k' being punctured or such diaphragm being omitted from the construction of such valve the chamber adjacent to arm e^5 is in communication with the atmosphere, so that air discharged into the valve from the conduit M is discharged into the atmosphere, and thereby the diaphragm of diaphragm-valve G is forced into a retracted position, as by springs g , and the valve opened for the admission of steam in the radiator I.

In the construction of this apparatus which I prefer the lever E is bent, as at e^6 e^7 , at right angles and tied together, as by cross-bars e^8 e^8 ; but whatever construction is used the parts are so related that the valves K K' will both be closed for a short time in the movement of such lever E to and fro by the expansion and retraction of the expandible member of the thermostatic valve and then one or the other of said valves will be opened, as hereinabove described.

In the operation of the thermostatic apparatus embodying this invention air under sufficient pressure to move the diaphragm in the chamber into which conduit M discharges will alternately be forced into such chamber and expelled therefrom, and thereby steam will alternately be admitted to radiator I from steam-supply pipe H through diaphragm-valve G and shut off from such radiator.

The thermostatic apparatus embodying this invention is made adjustable, so as to operate to automatically open and close, as described, the valves K K' at a desired temperature, such adjustability being obtained by means of the thumb-nut U and head D, fitting on the screw-threads u of the rod b' , there-

by forcing the head D into a desired position (as such head is slightly turned on the rod), and maintaining it in its adjusted position by setting the thumb-nut thereto. The figures 5 "65," "70," "75" at the upper end of the expansible member B indicate, approximately, in connection with pointer d the temperature at which the apparatus operates, as described, to shift the valves K K'—that is to say, when 10 the air immediately surrounding the thermostatic apparatus is at the temperature indicated by pointer d valves K K' will be closed and any material variation in the temperature of such air will cause either one or 15 the other of the valves K K' to be opened.

It is evident that where a temperature-controlled apparatus is not desired the lever E may be disconnected from the expansible member B, as by withdrawing the pivot e, 20 and that such lever may then be moved to and fro by the hands to open and close the valve G, and so admit steam to a radiator or shut steam therefrom at the will of the operator. It is also evident that the lever E and 25 valves K K', provided with a communicating passage-way, as by conduit E, in combination with a source of supply F containing air under pressure, a conduit J therefrom to one of the valves K, a conduit M from the 30 other valve K' to a chamber into which such last-named conduit discharges, may be used without the thermostatic device in any apparatus when a pressure corresponding with the 35 pressure in a source of air-supply is desired to be obtained alternately with atmospheric pressure in such chamber by hand manipulation of a lever E. It is also evident that except for ease of operation and liability of 40 leakage an ordinary stuffing-box may be substituted for the diaphragm k'.

Having thus described my invention, what I claim as new, and desire to secure by Letters Patent, is—

1. In a thermostatic heat-regulator, the 45 combination of an expansible member, a fulcrumed lever, a connection between the expansible member and the lever adjacent to the fulcrum of the lever, valve-casings provided, respectively, with valves coöperating 50 with valve-seats in the casings, such valves provided with stems extending adjacent to the lever, but not in contact therewith when both the valves are seated and the lever is in its midway position, means for yieldingly 55 holding the respective valves seated, a dia-

phragm at one end of one of the valve-casings interposed between the end of the valve-stem and the lever adjacent thereto, and such casing provided with an inlet for discharging air, under pressure, thereinto on one side of 60 the valve thereof and provided on the other side of such valve, and between the valve-seat therein and such diaphragm with a communicating passage-way extending from such casing to the second-named valve-casing and 65 discharging thereinto on one side of the valve therein, an outlet from such last-named casing on such side of the valve therein, such outlet communicating with a conduit discharging into the diaphragm-chamber of a dia- 70 phragm steam-valve, and an outlet to the atmosphere from the last-named valve-casing on the other side of the valve therein; substantially as described.

2. In an air-controlling device for a heat-regulating system, the combination of a primary or inlet air-chamber provided with an inlet air-duct, a secondary air-chamber, an air-duct communicating between the primary and secondary air-chambers, an outlet air-controlling valve located in the primary air-chamber, adapted to control the discharge of air therefrom into the secondary air-chamber, an air-duct communicating between the secondary air-chamber and an additional air-chamber, an additional air-chamber, an air-duct communicating between such additional air-chamber and a diaphragm air-chamber, of a steam-controlling valve, and an additional air-duct from the additional air-chamber 85 communicating with the atmosphere, an air-controlling valve located in the additional air-chamber adapted to control the escape of air therefrom; each of said air-controlling valves being provided with protruding valve-stems extending through the air-duct closed by the seating thereof, respectively, a thermostatically-actuated arm communicating with the protruding stems of the air-controlling valves, the thermostatically-actuated arm 90 adapted, as it moves in either direction, to engage and actuate the stem of one of said air-controlling valves as the other is automatically closed; substantially as set forth and described.

ALBERT M. BUTZ.
